CLAIM

The ornamental design for an armrest for chair of spa foot bath, as shown and described.

DESCRIPTION

FIG. 1 is a front perspective view of an armrest for chair of spa foot bath showing my new design;

FIG. 2 is an enlarged front perspective view of the armrest shown in isolation; and,

FIG. 3 is a side view thereof.

The broken line showing the remainder of the chair and spa foot bath in FIG. 1 is for illustrative purposes only and forms no part of the claimed design. The unshown portions of the armrest form no part of the claimed design.
